SEWING MACHINES

Cleo K. Dunkerly and Granvil L. Rushing, Jackson, Tenn., assignors to United Shoe Machinery Corporation, Flemington, N.J., and Boston, Mass., a corporation of New Jersey

Application July 11, 1956, Serial No. 597,260

6 Claims. (Cl. 112—60)

This invention relates generally to moccasin-type shoe sewing machines equipped with curved hook needles and more particularly to improvements in such machines fitted for operation upon one-piece shoe uppers to insert a U-shaped seam simulating that employed for joining the top piece or tongue and the side piece or vamp of a moccasin shoe upper.

In the manufacture of such one-piece shoe uppers from relatively thin material by conventional methods, difficulties have heretofore been encountered in forming the U-shaped moccasin seam. Because the materials used are often very flexible, the machine operator must possess a high degree of skill in presenting the upper to the machine. Furthermore, the seam tends to vary in thickness along its length where the material is thin and flexible. In addition, a seam which simulates a true moccasin seam lacks sufficient firmness and is therefore prematurely deformed as the shoe is worn.

To overcome these difficulties, it has been suggested that a string or filler cord be enclosed within the seam. Our invention is specifically concerned with the provision of improved means for directing such a cord into a seam inserted by a curved needle sewing machine and for retaining the cord in place as the stitches are being formed in a manner to prevent interference with the needle. The apparatus of our invention is useful in a sewing machine of the type shown, for example, in United States Letters Patents No. 1,975,914, granted October 9, 1934; No. 2,221,320, granted November 12, 1940, and No. 2,399,159, granted April 30, 1946, all upon application of Fred Ashworth. A work support having reentrant angularly disposed work engaging surfaces extending in the direction of work feed is shown in each of the above patents. For sewing a moccasin-type seam in a one-piece shoe upper to simulate a true moccasin seam in a two-part upper, and for purposes of ornamentation, the upper is presented to the sewing machine in the manner disclosed in the last-mentioned patent. A ridge simulating a true moccasin seam is raised automatically by the work supporting and clamping devices shown in this latter patent and, thereafter the ridge is retained by the tension of the thread in the seam.

It is a general object of the present invention to provide means, in a machine of the type above referred to, for accurately directing a filler cord into a simulated moccasin seam of a one-piece shoe upper, in a manner to improve the appearance of such seam with respect to uniformity and effective ornamentation. A further object is to facilitate the presentation of one-piece shoe uppers to a moccasin seam sewing machine while reinforcing the seam with a filler cord.

These and other objects are achieved in the illustrated embodiment of the invention by the provision of a moccasin seam sewing machine having stitch-forming devices, including a curved needle movable across the angle formed between work-engaging and compressing surfaces on a work support and a cooperating presser, in which

the presser is constructed with an eye through which the filler cord is passed for guiding the cord into the seam inserted by the stitch-forming devices. As hereinafter described, the angle between the work-engaging surfaces 5 on the presser is substantially the same as that of the work engaging surfaces of the work support and the cord guiding eye is located at the apex of the angle of said presser. In accordance with prior constructions, the presser is formed with three prongs alined in the direction of work 10 feed, and arranged to be engaged by the work and, preferably, the filler cord guiding eye is formed in the first prong of the presser, which is located in advance of the point of needle operation, and another prong acts on the cord beyond the point of needle operation to clamp the 15 cord against displacement during formation of each stitch. This feature of the invention also includes the formation of a second prong with a truncated shape and in this particular feature the connecting surfaces between adjacent prongs are convexly rounded with smooth curvatures to reduce the possibility of damage to the needle in 20 case of deflection against such surfaces.

The objects, features, and advantages of our invention will be clarified by the following detailed description of an illustrative embodiment thereof, taken in connection 25 with the accompanying drawing, in which:

Fig. 1 is a view in side elevation looking from the right and showing as much of a moccasin sewing machine as is necessary for an understanding of the present invention;

Fig. 2 is a detail view, on an enlarged scale and in side 30 elevation, of a presser embodied in the machine of Fig. 1, as seen from the right of the machine;

Figs. 3 and 4 are end and plan views, respectively, of the presser of Fig. 2; and

Fig. 5 is a view in perspective of a shoe upper having 35 a moccasin-type seam within which a cord is enclosed.

In the illustrative embodiment of our invention shown in Figs. 1 to 4, a three-pronged inner work-compressing presser, indicated at 6, cooperates with a work support, indicated at 8, for holding a shoe upper 10, shown in Fig.

40 5, during the formation of individual stitches of a seam 12. The work support 8, which consists of two parts, designated as 14 and 16, joined together by screws 18 is secured on a bracket 20 which is fixedly mounted on the machine frame. Both the work support and the presser are provided with work-engaging surfaces 21 disposed with the same angles of separation with an apex extending in the direction of work feed. The presser 6 is fixed by screws 22 to the upper end of a curved horn 24 pivoted for movement in the direction of the arrows in Fig. 1 and corresponding to the horn 40 of the machine disclosed in United States Letters Patent No. 1,975,914 above identified.

The machine is provided with conventionally operating lock stitch forming devices comprising an awl 26, a curved 55 hook needle 28, a loop spreader 30, and a loop taker or shuttle 32. Work feed is in the direction of the arrow in Fig. 4 and is accomplished by the awl 26 which pierces the upper 10, advances it toward the sewing point to bring the awl perforation into line with the needle 28, is withdrawn from the work, and returned to its starting point. Both the needle and awl move across the angles of the work engaging surfaces 21 to enter and emerge from the same side of the upper supported by the work support. The horn 24 swings slightly outwardly to move the presser 6 out of compressing engagement with the work to permit 60 the latter to be advanced by the awl 26. It is particularly important, in forming a cord filled moccasin type seam on a curved hook needle machine, to avoid injuring or severing the cord by the awl or by engagement with the needle as they penetrate the work. In order to obtain a seam of uniform appearance it is also necessary that each stitch

70

enclose the cord which is thereby pressed against the inner apex of the ridge. It will thus be appreciated that the cord must be under constant control of the presser to eliminate the possibilities either that the cord will be cut by the awl, or that the stitches will intersect the cord or will be formed between the cord and the inner apex in the shoe upper.

The presser 6 is provided with a first cord guiding prong 34, having at its apex an eye 36, a second truncated intermediate prong 38, and a third cord pressing prong 40, the latter only being disposed beyond the point of needle operation. By being threaded through the eye 36 the cord 42 is guided accurately into the inside of the ridge beyond the line of the seam to be inserted. The prong 40 has a slightly flattened, or, alternatively, grooved tip 41 which presses the cord firmly into the ridge of the seam 12 as the stitches are being formed. The pressing action of the prong 40 prevents random movement of the cord 42 and thus permits the formation of a highly uniform ridge. The three prongs 34, 38 and 40 have a profile which is substantially complementary to that of the reentrant work engaging surfaces 21 of the work support 8. Thus, the truncated prong 38 aids considerably in gripping and forming the upper 10 adjacent the sewing point, while permitting clearance for the awl 26 with minimum motion of the presser 6. The slots or spaces between adjacent prongs are formed with sufficient depth to permit passage of the awl and the needle behind the cord 42, thus protecting the cord against injury or severance. Convexly rounded surfaces 43 at the bottoms of the slots provide guide surfaces adjacent to the paths of the awl 26 and the needle 28 which greatly reduce the possibility of breakage in the event that the awl or needle is deflected or bent slightly outwardly. Taper of the presser 6 in the direction of feed, as indicated more particularly by the lines 44 in Fig. 3, facilitates closure of the ridge at the point of needle operation.

From the foregoing description many minor variations of our invention will be apparent to those of ordinary skill in the art. For example, the guide eye 36 need not be located adjacent the tip of the prong 34, but may be formed closer to the region in which the presser 6 is attached to the horn 24 and the cord 42 guided in a shallow groove over the prong 34. Accordingly, it is not intended to limit our invention to the arrangement and combination already described and shown for purposes of illustration, but rather to rely upon the definitions contained in the appended claims.

Having thus described our invention, what we claim as new and desire to secure by Letters Patent of the United States is:

1. In a machine for sewing a moccasin seam in a one-piece shoe upper having a work support provided with angularly disposed work-engaging surfaces extending in the direction of work feed, a horn mounted for movement toward and away from the work support, and stitch-forming devices including a curved needle movable across the angle of said surfaces to enter and emerge from the same side of the upper supported by the work support, the combination of an internal presser on the horn, said internal presser having work-engaging surfaces disposed at substantially the same angle as the work-engaging surfaces of said support to compress the material of the work between its work-engaging surfaces and those of the work support, and also having an eye means through which a cord passes for guiding the cord into the seam inserted by the stitch-forming devices.

2. In a machine for sewing a moccasin seam in a one-piece shoe upper having a work support provided with angularly disposed work-engaging surfaces extending in the direction of work feed, a horn mounted for movement toward and away from the work support, and stitch-forming devices including a curved needle movable across the angle of said surfaces to enter and emerge from the same side of the upper supported by the work support, the com-

bination of an internal presser on the horn, said internal presser having work-engaging surfaces disposed at substantially the same angle as the work-engaging surfaces of said support to compress the material of the work between its work-engaging surfaces and those of the work support, and also having an eye means at the apex of the work-engaging surfaces of said presser for guiding a cord into the seam inserted by the stitch-forming devices.

3. In a machine for sewing a moccasin seam in a one-piece shoe upper having a work support provided with angularly disposed work-engaging surfaces extending in the direction of work feed, a horn mounted for movement toward and away from the work support, and stitch-forming devices including a curved work-penetrating instrument movable across the angle of said surfaces to enter and emerge from the same side of the upper supported by the work support, the combination of an internal presser on the horn, said internal presser having work-engaging surfaces disposed at substantially the same angle as the work-engaging surfaces of said support to compress the material of the work between its work-engaging surfaces and those of the work support, said internal presser having a first prong in advance of the point of operation of the penetrating instrument, having an eye means through which a filler cord is guided into the seam, and also having another prong formed with a tip portion means which engages said cord adjacent to the point of penetrating instrument operation to clamp the cord against the upper during the formation of each stitch.

4. In a machine for sewing a moccasin seam in a one-piece shoe upper having a work support provided with angularly disposed work-engaging surfaces extending in the direction of work feed, a horn mounted for movement toward and from the work support, and stitch-forming devices including a curved work-penetrating instrument movable across the angle of said surfaces to enter and emerge from the same side of the upper supported by the work support, the combination of an internal presser on the horn, said internal presser having work-engaging surfaces disposed at substantially the same angle as the work-engaging surfaces of said support to compress the material of the work between its work-engaging surfaces and those of the work support, said internal presser having a first prong in advance of the point of operation of the penetrating instrument, having an eye means through which a filler cord is guided into the seam, and also having another prong formed with a tip portion means which engages said cord adjacent to the point of penetrating instrument operation to clamp the cord against the upper during the formation of each stitch, the space between said prongs having a depth greater than the combined thicknesses of the cord and the work-penetrating instrument to enable the passage of the work penetrating instrument without engaging the filler cord.

5. In a machine for sewing a moccasin seam in a one-piece shoe upper having a work support provided with angularly disposed work-engaging surfaces extending in the direction of work feed, a horn mounted for movement toward and from the work support and stitch-forming devices including a curved needle and a curved awl movable across the angle of said surfaces to enter and emerge from the same side of the upper supported by the work support, the combination of an internal presser on the horn, said internal presser having work-engaging surfaces disposed at substantially the same angle as the work-engaging surfaces of said support and three prongs in spaced relation with one another along the length of the seam, the first prong having an eye means through which a cord is guided into the seam, the second prong being truncated and shorter than the other prongs thereby permitting work feeding movement of the awl with a minimum movement of the horn away from the work support and located in advance of the point of needle operation, and the third prong being located beyond the point of needle operation in the direction of work feed and having a tip means engaging

said cord adjacent to the point of needle operation during the formation of each stitch.

6. In a machine for sewing a moccasin seam in a one-piece shoe upper having a work support provided with angularly disposed work-engaging surfaces extending in the direction of work feed, a horn mounted for movement toward and away from the work support, and stitch-forming devices including a curved needle and a curved awl movable across the angle of said surfaces to enter and emerge from the same side of the upper supported by the work support, the combination of an inner presser on the horn, said internal presser having work-engaging surfaces disposed at substantially the same angle as the work-engaging surfaces of said support and three prongs in spaced relation with one another along the length of the seam, the first prong having an eye means through which a cord is guided into the seam, the second prong being truncated and shorter than the other prongs thereby permitting

5

10

15

work feeding movement of the awl with a minimum movement of the horn away from the work support and located in advance of the point of needle operation, the third prong being located beyond the point of needle operation in the direction of work feed and having a tip means engaging said cord adjacent to the point of needle operation during the formation of each stitch, and convexly rounded surfaces between adjacent prongs to avoid damage to the needle in case of deflection against the presser.
